United States Patent Office

Des. 189,308
Patented Nov. 22, 1960

189,308

HOUSEHOLD MIXER

Philip E. Willman, St. Charles, Ill., assignor to McGraw-
Edison Company, Milwaukee, Wis., a corporation of Delaware

Filed July 28, 1960, Ser. No. 61,566

Term of patent 14 years

(Cl. D44—1)

Fig. 1

Fig. 1 is a perspective view of a household mixer embodying my new design;

Fig. 2 is a front elevation thereof; and

Fig. 3 is a side elevation thereof.

I claim:

The ornamental design for a household mixer, as shown.
